UNITED STATES PATENT OFFICE.

JOSEPH O. MAUBORGNE AND GUY HILL, OF WASHINGTON, DISTRICT OF COLUMBIA.

ANTENNA SYSTEM.

Application filed June 29, 1921. Serial No. 481,334.

To all whom it may concern:

Be it known that we, JOSEPH O. MAUBORGNE and GUY HILL, citizens of the United States, and residents, respectively, of Washington, in the District of Columbia, have invented certain new and useful Improvements in Antenna Systems, of which the following is a specification.

This invention relates to the art of radio signaling, and particularly to an antenna system for transmitting and receiving radio signals. The object of the present invention is to provide a new form of antenna consisting of a flat spiral wave coil, being in contradistinction to our pending United States applications bearing Serial Numbers 383720, filed May 24, 1920, 389450, June 16, 1920, 445880 filed Feb. 17, 1921, and a recently filed application, Ser. No. 459,530, filed April 8, 1921, wherein we have employed a resonance wave coil consisting of a helix; the flat spiral wave coil being of particular advantage where installation conditions are such that a flat coil could be installed to better advantage than one of helical form.

In our pending applications referred to above, we have described methods for receiving and transmitting radio signals in which resonance wave coils of helical form are introduced as a new type of antenna, utilizing the wave development effects produced by electrical excitation of such antenna, either from a distant source in the form of electro-magnetic waves acting upon it, in which case the wave coil serves as a receiving antenna, or the wave coil may be used as a transmitting antenna by setting up electrical oscillations in the coil from a local source, which may have a period of its own, in which case the coil is adjusted to be in resonance with the frequency of the oscillations of said source, or the period of the oscillations may be determined solely or mainly by the electrical constants of the coil, where the local source has no period of its own.

The present invention utilizes the same general idea except that in place of a wave coil in the form of a helix, as described in all of our previous applications referred to, we make use of a wave coil in the form of a flat spiral. This is the flat spiral resonance wave coil which we will herein-

after term, for the purpose of convenience, 55 "spiral wave coil."

The spiral wave coil forming this invention preferably consists of a length of suitably insulated conducting material wound in the form of a flat spiral of suitable size or dimensions such as conditions or preference may dictate, so that inductance, capacity and resistance are all of a distributed character and of such magnitude as to insure a wave development on 60 the coil for the frequencies of the signals desired to receive or transmit.

The wave coil is wound with a sufficient number of turns so that in a small space is produced the equivalent of a long antenna in the matter of natural electrical period.

In order that the invention and its mode of operation may be understood by persons skilled in the art, we have in the accompanying illustrative drawings and the detailed following description, set out one embodiment of the same.

In these drawings:

Figure 1 is a diagrammatic view, showing a spiral wave coil antenna wherein the convolutions thereof are arranged in a vertical plane, and

Figure 2 is a similar view showing the spiral wave coil with convolutions arranged 65 in a horizontal, or substantially horizontal plane.

Having more specific reference to the drawings in connection with which like characters of reference will designate corresponding parts throughout, and having especial reference to Figure 1, we have shown our spiral wave coil as consisting of a length of electrical conducting material, preferably insulating wire, indicated by the 70 reference character A, said length of wire being wound to form a flat spiral resonance wave coil including a large number of juxtaposed convolutions, such as clearly shown in the Figure 1. A variable contact, indicated by P, is provided on lead L so that connection can be made to any desired convolution of coil A, such lead, in turn, extending to and having connection with a radio transmitter or receiver, not shown. A 75 second lead, indicated by L', is shown connected to ground G, the other end of this lead going to the radio transmitter or ra-

dio receiver, as desired. As explained in our previous applications referred to above, the spiral resonance wave coil of this application, when substituted for the resonance wave coil of said previous applications, can be used as an efficient antenna either with or without a ground connection on the transmitting or receiving set.

Referring now to the arrangement of the spiral wave coil, illustrated in the Figure 2, it will be seen that instead of arranging the convolutions of said coil in a vertical plane, they are here placed in a horizontal, or substantially horizontal plane; the conducting material from which the spiral wave coil is formed being indicated by the reference character A', while the variable contact therewith is identified by the character P'. As described in connection with the Figure 2, a lead L₁ connecting the conducting P' extending to one terminal of a radio transmitter or a radio receiver, not shown. The opposite, or remaining terminal of the particular radio set upon which the coil is employed is connected to ground G by a lead L₂, if desired, although, of course, as hereinbefore stated, the use of this ground connection L₂ is optional.

It is also our intention to employ, in some instances, a plurality of these spiral coils, connecting the same in series, and connecting the lead, such as indicated at L, to any one of the coils as may be desired.

In the operation of the spiral wave coil, if a ground connection is used, the wave coil and tuning elements of the radio set and ground connection are all brought into tune with the wave length which it is desired to receive or transmit, the wave coil operating more and more efficiently as the natural period of the coil approaches the wave length being utilized for the transmission or reception, using only that amount of inductance in series with the coil and within the radio transmitter or receiver which may be necessary to obtain the desired coupling within the radio set. The natural period of the spiral coil will vary as the variable contact P is moved along the convolutions

of the coil; the longest wave length being obtained when the contact P is at one end of the coil as indicated in Figures 1 and 2.

In winding the spiral wave coil we have found that the turns of the coil should be comparatively closely wound so as to obtain a large inductance within a small diameter. The efficiency of the coil for transmitting and receiving increases as the height of the spiral wave coil about the set is increased. While the spiral wave coil in the drawings is shown in only two positions, that is, one in horizontal and one in a vertical plane, it is understood that any desired position of the wave coil can be employed.

Claims:

1. A resonance wave coil comprising a spiral of wire in the form of an open circuit having a fixed distributed inductance and capacity of such values that said spiral is capable of having developed thereon a number of standing waves corresponding to a wide range of frequencies, means for selecting the element of the spiral corresponding to the particular frequency desired, and means for connecting said selected element of said coil with radio communication apparatus, said last mentioned means comprising the only connection between the resonance wave coil and the radio communication apparatus.

2. A resonance wave coil comprising a spiral of wire in the form of an open circuit, unassociated with any antenna, ground, or counterpoise, and having a fixed distributed inductance and capacity of such values that said spiral is capable of having developed thereon a number of standing waves corresponding to a wide range of frequencies, means for selecting the element of the spiral corresponding to the particular frequency desired, and means for connecting said selected element of said coil with radio communication apparatus, said last mentioned means comprising the only connection between the resonance wave coil and the radio communication apparatus.
